SAFETY DEVICE FOR A PUNCH PRESS

Maurice R. Atkinson, Streetsville, Ontario, Canada, assignor to CTS of Canada, Ltd., Streetsville, Ontario, Canada, a corporation of Canada

Filed Sept. 27, 1962, Ser. No. 227,658

4 Claims. (Cl. 192—129)

This invention relates generally to safety devices for punch presses and in particular to a mechanism which will ensure that a punch press will make only one stroke each time its clutch is engaged.

Single stroke mechanisms are used throughout industry in connection with punch press operations. They are primarily installed for operator protection. Punch press operators get into a rhythm of loading and unloading the punch press dies and once their pattern of movements are established it is imperative that the punch press not make an additional unexpected stroke for invariably it will occur when the operator has his hands under the press. Even where there is no concern for operator safety because the parts are mechanically loaded it is important to use single stroke mechanisms to prevent damage to the loading mechanisms which would be under the die when the press makes its additional stroke. In addition to the above reasons, many of the tools and dies used in punch presses are subject to damage when operated empty. These tools and dies are expensive to build but they are even more expensive to repair or replace.

There are many different types of single stroke mechanisms on the market and in use today. It is the object of this invention to provide a single stroke mechanism which employs a minimum of parts and which has an unusually high degree of reliability.

It is a further object of this invention to provide a single stroke mechanism which will "fail safe" in that should it fail to operate properly, the clutch on the press will not be engaged.

It is an additional object of this invention to provide a single stroke mechanism which can be used either with a power operated press or a foot or hand operated press.

The invention consists of a device which is installed between the power cylinder or the foot pedal of the press whichever may be the case and the clutch pin disengaging mechanism. The device consists of a reciprocally mounted pull rod which is attached to the foot pedal or the cylinder rod of the air cylinder and a reciprocally mounted latch rod which is attached to the retaining member of the clutch. The latch rod is provided with a latch on the end adjacent the end of the pull rod. A latch dog is pivotally attached to the end of the pull rod and is designed to automatically engage the latch on the end of the latch rod when the pull rod is at the upper end of its stroke. A cam is provided in the housing and located so that the latch dog will be disengaged from the latch rod after the pull rod has moved the latch rod a sufficient distance to engage the clutch of the press.

In operation the foot pedal is depressed or the air cylinder energized and the pull rod moves downward pulling the latch rod with it. After it travels a short distance the latch rod disengages the clutch retaining means of the press allowing the clutch to be engaged which starts the press through its cycle. At this time the latch dog engages a cam in the housing which releases the latch dog from the pull rod allowing it to return to its first position where it disengages the clutch of the press. The length of travel and the time required for the draw bar to engage the clutch and then to be disengaged from the latch rod is arranged so that the clutch will be engaged only a sufficient length of

2

time for the press to make one cycle of operation. Once disengaged from the latch rod, the draw bar continues downward to the end of its stroke. It then returns to its original position where the latch dog will automatically reengage the latch bar preparatory to another cycle of operation.

By automatically releasing the latch rod from the remainder of the mechanism, the foot pedal can be held down or the air cylinder can be continuously energized yet the press will only perform one cycle of operation since the clutch cannot again be actuated until the draw bar is allowed to return to the top of its stroke.

The invention will now be described in detail in connection with the attached drawings in which:

FIGURES 1 and 1A are drawings in elevation of a typical clutch for a punch press with the single stroke mechanism showed installed;

FIGURE 2 is a vertical cross sectional view of the single stroke mechanism;

FIGURES 3 through 6 are schematic sectional views taken along line 3—3 of FIGURE 2 illustrating the relative positions of the components of the mechanism during one cycle of operation; and

FIGURE 7 is an enlarged sectional view of the latch dog engaging the draw bar at the end of a cycle of operation.

The invention is illustrated in the drawings in connection with the "pin clutch" used with the majority of punch presses. The device would equally be applicable to punch presses which use other types of clutches the only requirement being that the controlled member must reciprocate from an engaging to a disengaging position. The invention lends itself particularly to the "pin clutch" type of press and therefore it will be described in connection therewith.

These clutches are well known in the art and consist of three drive pins 10 which are spaced 120° apart and carried by the flywheel 9. Arranged to engage these flywheel drive pins is a clutch pin 11. The clutch pin in turn is held out of engagement with the drive pins by means of a latch block 12. The latch block is tapered and is arranged so that when in the position shown in FIGURE 1 it will either hold the clutch pin out of engagement with the flywheel drive pins or it will engage the rotating clutch pin and disengage it from the flywheel pins. In other words once engaged the clutch pin can only make one revolution if the latch block is returned to the position indicated before the flywheel completes one revolution. One revolution is of course sufficient for one cycle of the punch press and it is this principal that makes the use of a single stroke mechanism possible.

The latch block is removed from its holding position against the clutch pin 11 by the linkage illustrated. The latch block 12 is carried by the arm 13 which is rotatably mounted to the press frame (not shown) by the pin 14. Attached to the arm 13 between the clutch pin and the pivot pin is the link 15 which is in turn pivotally mounted to the crank arm 16 by the pin 17. The crank arm 16 is rotatably mounted to the frame of the press by the pin 18. Attached to the end of the crank arm 16 by the pin 20 is the clutch rod 19 through the pin 20. The clutch rod 19 passes through a pair of springs 21 and 22 which combine with the bracket 23 and the collars 24 attached to the rod to exert an upward force on the rod 19 so that it will return the linkage to the clutch disengaging position indicated when no downward force is being exerted on the rod. In other words when no force is being exerted on the clutch rod 19 the clutch will be disengaged. To engage the clutch the rod 19 must be moved downward compressing the springs 21 and 22, rotating the crank arm 16 so that the link 15 causes

the arm 13 to rotate a sufficient distance around the pin 14 to remove the latch block from its holding position adjacent the clutch pin 11.

This is a typical linkage arrangement used with this type of clutch and can be actuated by either an air or hydraulic cylinder or a foot or hand pedal. In FIGURE 1A an air cylinder is illustrated which is indicated generally by the number 25.

The single stroke mechanism of the invention is indicated generally by the number 27. It is installed between the piston rod 32 of the air cylinder and the clutch rod 19. The air cylinder is pivotally mounted to the frame of the press by the bolt 26.

The single stroke mechanism of the invention consists of the housing 30 which is rigidly attached to the air cylinder 25 by means of the bracket 31. Reciprocally mounted in the housing and attached to the piston rod 32 is the pull rod 33. The pull rod is made up of two identical members 33a and 33b, which extend the length of the housing and which carry the latch dog 34 between them by means of the pin 35. Reciprocally inserted between the two members of the pull rod is the latch rod 36 which extends out of the upper end of the housing and is attached to the rod 19 of the press operating mechanism by the pin 45. Extending through the housing is the pin 37 which engages the slot 38 in the latch rod and the slot 45 in the pull rod to limit their travel in both directions. Also mounted in the housing is the cam 39.

Operation

The above description sets out the individual components of the single stroke mechanism. Now its operation will be described so that the inner relationship of all of these components can be fully understood.

In FIGURES 3-7 a complete cycle of operation of the device is illustrated. In these views part of the housing 30 has been removed to clearly show the relationship of the working parts. In FIGURE 3 the mechanism is in the position of FIGURE 1 where the clutch is disengaged.

The operator then presses the control to operate the press. This allows air under pressure to enter the air cylinder 25 and move the piston rod 32, the pull rod 33, the latch dog 34, and the latch rod 36 downwardly to the position shown in FIGURE 4. This movement is sufficient to cause the latch block 12 to release the clutch pin 11 and engage the clutch.

It is at this instant as illustrated in FIGURE 5 that the cam 39 begins to force the latch dog to pivot on the pin 35 by which it is attached to the pull rod and release the latch rod. In other words, the inner engaging surfaces 41 on the latch dog and 42 on the latch rod will be forced out of engagement with each other by the action of the cam 39 thus releasing the latch dog from the pull rod. When this occurs the springs 21 and 22 force the clutch rod and the latch rod back to the clutch disengaging position of FIGURE 1 while the pull rod continues downward. This condition is shown in FIGURE 6.

The air cylinder rod 32 will continue on downward until the piston reaches the end of its stroke and will stay in this position until the air supply is reversed. If a foot pedal is being used in place of the air cylinder and as long as the foot pedal is depressed, the pull rod will remain in the down position. The length of time that the air cylinder or the foot pedal is held in this position will have no effect whatsoever on the operation of the press because it will have made just one cycle before the clutch was disengaged again by the latch block.

FIGURE 7 illustrates the position of the latch dog when the air cylinder is being returned to its original position. Just prior to the end of its upper travel the cam surface 43 on the latch dog engages the end 44 of the latch bar which will in turn rotate the latch dog around the pin 35 into position so that the surfaces

41 and 42 will be reengaged preparatory to operating the press again.

As pointed out above the pin type clutch lends itself to this type of mechanism very readily since it is so constructed that once the clutch pin has engaged the flywheel pins it will complete one cycle of operation before it can again be disengaged by the latch block. In this way the action of the mechanism can be very rapid and the distance traveled by the latch rod need only be sufficient to remove the latch block an extremely short period of time after which it can be released and allowed to return to its disengaging position. In other words the action of this mechanism is such that it will disengage the latch rod allowing it to return to its original disengaging position immediately after the clutch pin has engaged one of the drive pins 19. In this way there is no possibility of the press making more than one cycle of operation each time it is energized.

Another important feature of this invention is that if for some reason the latch dog should fail to engage the latch rod or if they should become inadvertently or prematurely disengaged before they reach the cam, the operator or the tools will not be placed in any danger since the malfunction will simply cause the press not to operate.

While there has been illustrated and described what is at present considered to be a preferred embodiment of the present invention, it will be appreciated that numerous changes and modifications are likely to occur to those skilled in the art, and it is intended in the appended claims to cover all those changes and modifications which fall within the true spirit and scope of the present invention.

The invention claimed is:

1. In a safety device for a clutch operated punch press, the combination of a housing, a pair of pull rods vertically disposed in spaced parallel relationship in the housing and fixedly secured to each other, a latch dog pivotally mounted intermediate the pull rods and provided with a cam surface, an upwardly biased rod slidably mounted for limited movement intermediate the pull rods and having one end detachably connected to the latch dog, the other end of the latch rod being connected to the clutch of the punch press, and a cam fixedly mounted in the housing for tripping the latch dog whereby upon moving the pair of pull rods downwardly the latch rod connected to the latch dog moves downwardly therewith to engage the clutch of the press and upon further downward movement of the pull rods the cam trips the latch dog and releases the latch rod to disengage the clutch.

2. In a safety device for a clutch operated punch press, the combination of a housing, a pair of pull rods vertically disposed in spaced parallel relationship in the housing and fixedly secured to each other, each of the pull rods being provided with an elongated slot, a pin fixedly mounted in the housing and having its central portion disposed in the elongated slots for limiting movement of the pull rods with respect to the housing, a latch dog pivotally mounted intermediate the pull rods below the elongated slots and provided with a cam surface, an upwardly biased latch rod having an elongated opening in alignment with the elongated slots provided in the pull rods and slidably mounted for limited movement intermediate the pull rods, the adjacent ends of the latch dog and the latch rod being detachably connected to each other, a cam disposed in the housing for tripping the latch dog, and means connected to the pair of pull rods for moving the pull rods downwardly to actuate the punch press whereby as the pull rods and the latch rod engaged to the latch dog are moved downwardly, the cam surface of the latch dog engages the cam thereby pivoting the latch dog out of engagement with the latch rod and causing the latch rod to slide upwardly a limited distance and disengage the clutch to halt operation of the punch press.

3. In a safety device for a clutch operated press, the

combination of a housing, a pair of vertically disposed pull rods in spaced parallel relationship mounted in the housing and fixedly secured to each other, an upwardly biased latch rod slideably mounted intermediate the upper portions of the pull rods, the upper end of the latch rod being connected to the clutch of the press for engaging the clutch upon downward movement of the latch rod, means for limiting the slideable motion of the latch rod with respect to the pull rods and of the pull rods with respect to the housing, a latch dog pivotally mounted intermediate the pull rods having one end detachably connected to the latch rod, and a cam mounted in the housing for tripping the latch dog whereby upon moving the pull rods downwardly the latch rod detachably engaged to the latch dog moves downwardly engaging the clutch for operating the press and upon further downward movement of the pull rods the latch dog is pivoted out of engagement by the cam thereby disengaging the connection between the latch rod and the latch dog permitting the latch rod to slide upwardly a limited distance and disengage the clutch of the press while the pull rods are still downwardly disposed.

4. In a safety device for a punch press, the combination of a housing, a pair of vertically slideable pull rods mounted in spaced parallel relationship in the housing, a lost motion connection provided between the housing and the pair of pull rods for limiting movement therebetween, a latch dog pivotally mounted intermediate the pull rods below the lost motion connection, a latch rod slideably disposed intermediate the pull rods above the latch dog and connected to the lost motion connection for limiting

the motion of the latch rod with respect to the pull rods, the adjacent ends of the latch dog and the latch rod each being provided with engaging shoulders, the other end of the latch rod being connected to a clutch rod of the punch press for operatively controlling the clutch of the punch press, a cam fixedly mounted in the housing for tripping the latch dog, and means connected to the pair of pull rods for moving the pull rods downwardly whereby upon downward movement of the pull rods the latch rod detachably engaged to the latch dog moves downwardly for engaging the clutch of the punch press and as the pull rods continue to move downwardly the latch dog engages the cam thereby pivoting the shoulder of the latch dog out of engagement with the shoulder of the latch rod causing the latch rod to slide upwardly until limited by the lost motion connection and disengage the clutch of the press.

the motion of the latch rod with respect to the pull rods, the adjacent ends of the latch dog and the latch rod each being provided with engaging shoulders, the other end of the latch rod being connected to a clutch rod of the punch press for operatively controlling the clutch of the punch press, a cam fixedly mounted in the housing for tripping the latch dog, and means connected to the pair of pull rods for moving the pull rods downwardly whereby upon downward movement of the pull rods the latch rod detachably engaged to the latch dog moves downwardly for engaging the clutch of the punch press and as the pull rods continue to move downwardly the latch dog engages the cam thereby pivoting the shoulder of the latch dog out of engagement with the shoulder of the latch rod causing the latch rod to slide upwardly until limited by the lost motion connection and disengage the clutch of the press.
